UNITED STATES PATENT OFFICE.

WM. HAILES, OF ALBANY, NEW YORK.

IMPROVEMENT IN GRATES FOR COAL STOVES AND FURNACES.

Specification forming part of Letters Patent No. **36,950**, dated November 18, 1862.

To all whom it may concern:

Be it known that I, WM. HAILES, of Albany, in the county of Albany and State of New York, have invented certain new and useful Improvements in Stove-Grates; and I do hereby declare that the following is a full, clear, and exact description of the same, reference being had to the accompanying drawings, and to the letters of reference marked thereon.

The nature of this invention consists in constructing a circular or that kind of grate which is agitated from a center on a level in such a manner that the spaces or peculiar springs between the bars increase in size or area from the periphery to the center to compensate for the decrease of motion, so that the grate will, when agitated, relieve itself from impurities, clinkers, and ashes equally all over its surface, thereby enabling me to keep the fire running for an indefinite period of time without dumping or emptying the fire-pot, the importance of which cannot be overrated; also, in the peculiar construction and arrangement of the bar under the grate when used with the grate, as will be set forth.

In the figures, A represents the circular grate, which has three arms uniting in its center, at the junction of which a pin or rod passes down from the under side, in order to secure it to the bar B, over which it oscillates or partially rotates. Upon the inner rim of this grate are a series of long projections, b b, and short ones a a, so adjusted or arranged that the ash-space is greater near the center than

it is about the circumference, to compensate for the increase of motion from the center to the rim, thereby enabling the grate to discharge equally over its whole surface.

B represents the bar on which the grate rests. This bar has a loop, C, cast in it, through which the projection D, which is cast to the grate, plays. The projection D plays in the loop, and the size of the loop forms the limit of the movement of the grate. The pin on the under side of the grate passes through the bar B, as is seen, and is secured by means of a nut, as shown in Fig. 2.

d d represent a series of projections cast upon the periphery of the rim, which serve as shakers and agitators when the grate is moved, to prevent the accumulation of ashes and the consequent clogging of the grate.

I do not claim any particular form of opening in the grate, as other forms will answer.

I am aware that grates have been made with bars running to the center. Therefore I do not claim such; but

What I do claim is—

The projections d d on the outer periphery of the grate, in combination with the inner projections a b, and with the looped bar in operating the grate, substantially as above described.

WM. HAILES.
